UNITED STATES PATENT OFFICE.

WALTER RIEFSCHNIDER AND HENRY RIEFSCHNIDER, OF SEATTLE, WASHINGTON.

SAFETY RAIL JOINT.

Application filed April 10, 1922. Serial No. 551,162.

To all whom it may concern:

Be it known that we, WALTER RIEFSCHNIDER and HENRY RIEFSCHNIDER, citizens of the United States, residing at Seattle, county of King, and State of Washington, have invented a new and useful Safety Rail Joint; and we do hereby declare that the following is a full, clear, and exact specification, such as will enable others skilled in the art 10 to which it appertains to make and use the same.

The invention is a means for connecting rails that will make it impossible for them to become disconnected or to bend at the 15 connecting point.

The object of the invention is to provide rails with ends which will dovetail together so that it will be impossible for them to spread without tearing up the entire track.

20 With these ends in view the invention embodies a rail with the top of the rail omitted a short distance from the end, its web thickened at the end and a tapering slot in the center of the web; and another rail with 25 angle plates extending beyond the end of the rail and integral therewith, slots between the angle plates and the web of the rail and the web slightly thickened and tapering.

Other features and advantages of the invention will appear from the following description taken in connection with the drawings, wherein:

Figure 1 is a side elevation with parts broken away.

35 Figure 2 is a cross section thru the joint.

Figure 3 is a bottom view of the female member.

Figure 4 is a perspective view of the male member.

40 In the drawings we have shown our joint as it would appear in use in Figure 1 wherein numeral 1 indicates one rail on which is the female joint and numeral 2 indicates another rail the end of which constitutes the 45 male member. The web of the rail 1 is thickened from the point 3 shown in Figure 1 and tapers from its upper end 4 to its lower end 5 where it is curved. On each side of this web are slots 6 and 7 and on the outside of 50 the slots are the angle plates 8 and 9 which are fastened to the top of the rail at their upper sides and to the web back of the point 3. These angle plates extend beyond the end of the rail 1 to a point 10 on the rail 2 which 55 should be a suitable distance from the end of the rail to allow space for bolts to hold

the rails. The upper inner surfaces of the plates 8 and 9 are beveled as shown at 11 and 12.

The top of the rail 2 is omitted for a short 60 distance from the end of the rail and the web is thickened from the point 10 to the end of the rail forming two bars 13 and 14 which fit into the slots 6 and 7 of the rail 1 and a tapering slot 15 into which the web at the 65 end of the rail 1 fits. The upper edges of the bars 13 and 14 are beveled at the points 16 and 17 to correspond with the surfaces 11 and 12 in the rail 1 and their outer ends slant backward from the point 20. Holes 18 70 may be placed thru the joint thru which the bolts 19 may be placed to bolt the joint together.

It will be understood that changes may be made in the construction without departing 75 from the spirit of the invention. One of which changes may be in the omission of the flanges on the bottom of the plates 8 and 9. Another may be in the number of bolts used in either section of the joint. And still another change may be in the shape of any of the members of the joint.

The construction will be readily understood from the foregoing description, as all rails may be made with one end similar to 85 that of rail 1 and with the other similar to that of rail 2 so that when a track is being laid one rail will fit into another and they may be bolted together. It will be seen that by joining rails in this manner it will be 90 absolutely impossible for them to come apart even though the bolts may loosen.

Having thus fully described the invention what we claim as new and desire to secure by Letters Patent, is:

1. A safety rail joint comprising two abutting rail ends one of which has the upper section cut away and the web provided with a central longitudinal groove extending from the point at which the upper sections is cut away to the end of the rail and the other of which is provided with a central web adapted to fit into said groove and integral splice plates spaced from said web and extending beyond the end of the rail to engage the sides of the first mentioned rail, said plates and webs being provided with bolt holes so that the joint may be bolted together.

2. A safety rail joint of the type described 110 comprising a rail end with the bottom flange removed for a short distance from the end

of the rail, the web thickened and having two longitudinal grooves in it extending upward to the bottom of the head of the rail and backward to the point at which the bottom flange is cut away, and another rail end with the head of the rail cut away for a short distance from the end and having a central longitudinal groove in the web extending from the bottom of the head of the rail to the top of the bottom flange and from the point at which the top of the rail is cut away to the end of the rail, said webs having holes for bolts through them.

3. A device of the type described embodying two side plates attached to the end of a rail and extending beyond the end; the bottom of the rail being cut off for a short distance from the end; a web between the side plates leaving a slot on each side of it; holes through the web and plates; the top of another rail being removed for a short distance from the end; bars on the sides of the web of the rail to fit into the slots of the former rail; a slot between these bars to admit the web of the former rail; and holes through the bars by which the joint may be bolted together.

4. A device of the type described embodying two side plates attached to the web of a rail at one end which extend beyond the

end of the rail; the bottom flange of the rail being removed for a short distance from the end; a web between the side plates leaving a slot on each side; holes through the web and plates; the top of another rail being removed for a short distance from its end; bars on the sides of the web of the rail to fit into the slots at the end of the former rail; a slot between these bars to admit the web of the former rail; and holes through the bars by which the joint may be bolted together.

5. A safety rail joint of the type described embodying a female member on the end of one rail having a web in its center; side plates attached to the rail extending beyond the end and leaving a slot on each side of the web and a male member with two bars spaced apart to fit into the two slots of the former member.

6. A safety rail joint of the type described embodying a rail whose top extends beyond its bottom and having side plates attached to it which extend beyond the end of its top; in combination with another rail whose bottom extends beyond the top and which has two bars extending upward from its bottom leaving a slot between them.
